UNITED STATES PATENT OFFICE.

FISK RUSSELL, OF BOSTON, MASSACHUSETTS.

IMPROVEMENT IN MOWING-MACHINES.

Specification forming part of Letters Patent No. 12,463, dated February 27, 1855.

To all whom it may concern:

Be it known that I, FISK RUSSELL, of Boston, in the county of Suffolk and State of Massachusetts, have invented a new and useful Machine for Mowing Grass; and I do hereby declare that the same is fully described and represented in the following specification and the accompanying drawings; letters, figures, and references thereof.

In the said drawings, Figure 1 denotes a top view of the machine. Fig. 2 is a side elevation of it, taken on that side on which the primary or driving wheel is situated. Fig. 3 is an elevation of the opposite side of it. Fig. 4 is a longitudinal section of the knife or cutter-bar, and exhibits the arrangement of the knives and the manner in which they are applied thereto. Fig. 5 is a transverse sectional view of the driving-cam and the bifurcated rocker-frame and lever thereof. Fig. 6 is a transverse section of the cutter-bar and its cutters, the same being made to exhibit a sectional view of one of the guard-teeth. Fig. 7 is a top view of one of the knives as separated from the machine.

In the said drawings, A represents a carriage or main rectangular frame, supported on two wheels, B C, the former being a driving as well as a supporting wheel—that is to say, its periphery is armed with a series of projections or teeth, *a a*, extended from it, as in the wheels of the well-known reaping-machines. This wheel carries on the inner surface of its rim an internal gear, *b*, into which a pinion, *D*, affixed to one end of a driving-shaft, *E*, is made to engage. This driving-shaft extends across the frame and is supported in boxes, as seen at *c c*, and carries a cam-wheel, *F*. The axis of the secondary wheel, *C*, is not disposed in line with that of the primary wheel, *B*, but is arranged aside from the same, and so that the secondary wheel shall be disposed entirely on one side of the driving or cam-shaft, it being understood that the two wheels are made of the same or about the same diameter.

By arranging the wheel *C* with respect to the wheel *B* as seen in the drawings, I am enabled not only to obtain the advantage of the second wheel, *C*, to support the frame-work near to the cutters, but also to have it of the same diameter as the wheel *B*, and to gain the very important advantage of employing the shaft *E* and cam-wheel *F* without any interference of the wheel *C* with them.

It will readily be seen that if the axis of the wheel *C* were placed in a straight line with that of the wheel *B* the wheel *C*, made of the same diameter of the wheel *B*, could not be used, as it would extend into the path of the shaft *E* and prevent such shaft from being employed to carry motion from the driving-wheel. It may be said that the wheel *C* could be made with its diameter smaller than that of the wheel *B* and arranged with its axis below that of such wheel; but under such circumstances not only would its axle be likely to interfere with the operations of the inclined lever *G*, but owing to the decreased diameter of the wheel an increase of the power of draft would naturally result.

In machines of this character so much of the strength of animals employed to draw them over the ground is required to put and maintain their operative mechanism in action that it becomes necessary to lessen as much as possible the friction of the wheels or their tendency to increase the power of draft. Thus it will be seen that important advantages are gained by the peculiar arrangement of the secondary supporting-wheel with respect to the driving-wheel and the driving-shaft.

The cam is so formed as to impart a reciprocating vibrating movement to an inclined lever, *G*, which works on a fulcrum at *H*. The said lever carries a bifurcated rocker-frame, *I*, that is made to turn in one end of the lever and to clasp the serpentine edge of the cam-wheel, and to carry two friction-rollers, *d e*, they being placed on opposite sides of the cam-wheel. By means of the rocker-frame the cam-wheel is enabled to operate the lever to much better advantage and with less noise and friction than would be the case were the lever applied to the cam by means of a stationary fork or its equivalent. Besides this, another advantage results from the peculiar application or use of a rocker-frame, the same being that it accommodates itself to the curves of the cam and so as to prevent improper lateral strain on the lever. The lower end of the lever extends into a mortise made in a long slide-bar, *K*, that is supported so as to slide in a groove formed in the cutter-bar *L*, that is fastened to and extends from a holdfast, *M*, as seen in the drawings, the said holdfast being a bent piece of metal formed and made to extend down therefrom, as seen in Fig. 3. The

said cutter-bar has projected from it a series of guard or hook teeth, as seen at N N N, between each two of which a movable oscillating tooth, O, is made to play, the said tooth being made to turn horizontally upon a center pin or fulcrum, f, extended upward from the cutter-bar. In the construction of these teeth they are formed triangular, or approximating thereto, in shape, and two of them are made to extend in opposite directions from one common center plate or bar, g, as seen in the drawings. Each of these teeth has a round hole, h, formed through it, each hole being at an equal distance from the hole i of the central plate. The lever-teeth so formed are arranged on the cutter-bar as seen in the drawings, their central holes being supported on stationary fulcra or pins f f f, while the back or rearmost holes are made respectively to receive pins k k k, extending upward from the slide-bar K. When the teeth are so arranged they may be covered by a cap-plate, P, made to extend partially over them, as seen in the drawings. By the reciprocating longitudinal movement of the slide-bar each of the cutting-teeth directly between each two of the guard-teeth will have imparted to it an oscillating movement, such as will not only cause it to cut with a guard-tooth, like a common pair of scissors, but with a slight drawing stroke, such as will impart to it a great advantage in severing grass. Should any one of the teeth become dulled or injured, it may be removed from its fulcrum and turned around over the sliding bar, so as to bring its fellow-tooth into its place. The fellow tooth, having been placed under the cap-plate of the cutter-bar, will have been protected from injury by such cap-plate.

To the outer end of the cutter-bar I affix a raking-board, Q, and I construct such raking-board in the following manner, the object of it being to move the cut grass away from the standing grass. Such board is made in two

independent parts, l m, each of which is affixed to the raking or cutting bar, the back board being applied thereto by a spring, n, which allows it to play up and down and slide on the front board while the latter is stationary.

I apply to the main frame of the machine, or I arrange and combine with the cutter-bar adjacent to and in rear of its junction with the main frame and in rear of the cutter immediately next thereto, a grass mowing or raking board, R, the same being applied so as to turn over and away from the frame the cut grass of a swath in order that when the machine is turned over and made to cut that over which it was previously carried there may be a clear path for the knife-bar holdfast to travel in. Without the application of the raking-board in the above-described manner such path would be likely to be obstructed by the cut grass or grain, and to an extent disadvantageous to the correct operation of the machine.

Having thus described my invention, what I claim is as follows. I do not claim the supporting of the frame of a mowing-machine on two or more wheels; but what I do claim, when two wheels only are employed for the support of such frame, is the above-specified arrangement of the secondary supporting-wheel with respect to the main driving and supporting wheel and the driving-shaft, such arrangement consisting in placing the axis of the secondary supporting-wheel aside of and not in line with that of the primary wheel and disposing the secondary wheel back of or on one side of the driving-shaft, so as to operate essentially as described.

In testimony whereof I have hereunto set my signature this 29th day of August, A. D. 1854.

FISK RUSSELL.
